PERFORATE TABLE

Walter F. Ohme, Minneapolis, Minn., assignor to
North Star Specialty & Manufacturing Com-
pany, Minneapolis, Minn., a corporation of
Minnesota

Application February 1, 1937, Serial No. 123,380

3 Claims. (Cl. 141--9)

Fig. 4 is a perspective view of one of the tie members of the table shown in Fig. 2.

Fig. 5 is an inverted perspective view of a portion of the structure shown in Fig. 2 with one of the tie members detached from the supporting members. 5

In order to more fully explain the application and operation of the invention my improved table has been shown as embodied in a machine for washing drinking vessels and only so much thereof as will be needed to explain the instant invention will be described.

The machine for washing drinking vessels herein illustrated comprises a housing which I have indicated in its entirety by the reference character A and in which the mechanism of the machine is disposed. The washing mechanism of the invention comprises a revoluble rack B of which my improved table forms a part and which is driven through a water motor C. The drinking vessels to be washed are carried by the rack B and as the same travels water is sprayed into and over the vessels by means of a spraying device D. These various parts will now be more fully described.

The housing A consists of a tray 10 circular in form which is constructed with a bottom 11 having a rim 12 extending upwardly therefrom. The bottom is preferably sloping toward the forward portion of the tray where a drain 13 is provided by means of which the water discharged into the housing may be removed from the device. At the outer margin of the bottom 11 is provided a ledge 14 which elevates the bottom 11 above the surface on which the machine rests. This ledge may, if desired, be formed in continuation of the rim 12 of said tray. The tray 10 is constructed as a casting or the same may be spun from sheet metal or constructed in any other suitable manner. The housing A further comprises a circular wall 15, which is secured to the rim of the tray 10 and extends upwardly therefrom. The lower edge of this wall rests in a recess 17 formed in said rim. The wall 15 is preferably attached to said rim through small bolts 16 which pass through suitable openings in both said rim and wall. Upon the upper end of the wall 15 is placed a cover or closure 18 which is circular throughout the extent thereof. This closure is provided with a flange 20 which extends downwardly therefrom and which terminates at its lower end in a lip 21 by means of which the closure may be secured to the wall 15. This is accomplished through bolts 22 which pass jointly through said wall and lip the same as the bolts 16. The wall 15 is of lesser circular 30 35 40 45 50 55 60 65 70 75 80 85 90 95 99

My invention relates to perforate tables and particularly to tables for use in supporting drinking vessels or other dishes which are being washed by means of sprays of water which pass through the table from beneath and wash the vessels while resting upon the table.

An object of the invention resides in providing a perforate table which will offer a minimum amount of resistance to the flow of water through the same.

Another object of the invention resides in providing a perforate table by means of which more thorough washing of the drinking vessels carried by the same can be procured.

15 A still further object of the invention resides in providing a perforate table constructed so that the supporting surface thereof will contact with the vessels over a minimum area.

Another object of the invention resides in constructing the table with spaced supporting members constructed from flat strips of metal arranged on edge so that the vessels rest upon the edges of said supporting members.

A feature of the invention resides in constructing the supporting members from flat wire with rounded edges so as to procure point contact between the supporting members and vessels.

Another object of the invention resides in providing tie members between said supporting members for holding the same in proper spaced relation.

A still further object of the invention resides in forming the supporting members circular and of different diameters and in arranging the same in concentric relation.

35 An object of the invention resides in arranging the tie members in radial relation with respect to the supporting members.

Another object of the invention resides in the specific construction of the joints between the supporting members and tie members and the joints at the ends of the supporting members.

Other objects of the invention reside in the novel combination and arrangement of parts and in the details of construction hereinafter illustrated and/or described.

In the drawings:

Fig. 1 is a medial elevational sectional view of a machine for washing drinking vessels illustrating a perforate table embodying my invention.

Fig. 2 is a plan view of the table detached from the machine.

Fig. 3 is a perspective view of one of the circular supporting members of the table shown in Fig. 2.

extent than a complete circle so that an opening 23 is provided at the front of the housing through which access may be had to the interior thereof and to the drinking vessels placed upon the rack 5 B mounted therein.

The rack B consists of a perforate table 24 which constitutes the invention. This table is constructed with a number of circularly formed concentrically arranged rings 25, 26, 27, 28, 29, 10 30, 31, 32 and 33. The rings 26 to 32 inclusive are all constructed in the same manner and the rings 25 and 33 are similarly constructed in the same manner. The description of the rings 25 and 26 will hence only be given.

15 All of the rings as shown in the drawings are constructed from flat strips of metal such as is known in the trade under the name of "flat wire", which is formed with flat sides and with slightly rounded edges. For the sake of simplicity the rings have been shown in the drawings as being 20 rectangular, whereas in actuality the corners are slightly rounded. It can, however, be readily comprehended that square corners, such as shown may be employed instead of the rounded edges 25 referred to.

25 The ring 25 is of the greatest diameter and is formed at one end with a dovetailed slot 35. The other end of the said ring is constructed with a dovetailed tongue 36 which is adapted to fit in the slot 35 and to form a lock joint for the end 30 of the ring. All of the other rings are similarly constructed with like joints of which only certain of said joints have been shown in the drawings. At suitable intervals throughout the 35 peripheral extent of the ring 25 the same is constructed with punched rectangular openings 34 which extend completely through the same. These openings are preferably equally spaced and in the instant case six of such openings are 40 employed.

45 The rings 26 to 32 inclusive are of slightly less width than the rings 25 and 33 and are so disposed that the rings 25 and 33 form guards to prevent the glasses or dishes from sliding off from the rack.

50 The ring 26 as shown in Fig. 3 is constructed at one end with a dovetailed slot 37 and at its other end with a dovetailed tongue 38 which fits into the same and forms a joint for the ring 25. This 55 ring is constructed with a number of notches 39 which extend through the lower edge of the ring and upwardly to the center of the ring. These notches are equally spaced and there are as many of the said notches as there are openings 34 in the ring 25.

55 In conjunction with the various rings a number of tie members 41, 42, 43, 44, 45 and 46 are employed which are all identical in construction. Only tie member 41 has been illustrated in detail in the drawings which will be described. This tie member is constructed of flat wire the same as the rings, but is straight and of a width equal to the width of the rings 26, 27, etc. This 60 tie member is constructed at one end with a tongue 47 which provides shoulders 48 at the end of the strip adjacent said tongue. The other end of the strip is similarly constructed with a tongue 51 providing shoulders 52 adjacent the 65 same. Intermediate the ends of the strip are provided notches 53 in the uppermost portion thereof which are of a depth equal to half the width of the strip and of a width equal to the thickness of the material from which the rings 70 26 to 32 are constructed. The tongues 47 and

51 are of such dimensions as to be snugly received within the openings 34 in the rings 25 and 33.

Before assembling the parts of the table, the various rings are first connected together at 5 their ends and the joints between the ends of the rings preferably soldered. The outer ring 25 is first assembled upon the ends of the tie members 41 to 46 with the tongues 47 received within the openings 34 and with the shoulders 10 48 bearing upon the inner surface of this ring. The inner ring 33 is then similarly applied with the tongues 51 received within the openings 34 and the shoulders 52 bearing against the outer 15 surface of said ring. Tongues 47 and 51 are 20 next riveted over so that the parts become securely attached to one another. The rings 26 to 32 are next successively assembled one at a time by bringing the notches 39 thereof into co-operation with notches 53 of tie members 41 to 25 46. After all of the rings have been assembled the joints are closed either by soldering, riveting or otherwise to provide a unitary structure 30 in which all of the parts are firmly secured together and in which the supporting surfaces 25 thereof consist of the edges of the various supporting members or rings.

It will be noted that all of the edges of the supporting members 26 to 32 inclusive lie in a common plane, while the edges of the members 30 25 and 33 extend upwardly from said plane to form guards for preventing the drinking vessels 35 from sliding off from the table.

The table 24 is rotatably supported on a spider 61 which comprises a central tubular hub 62 connected to a circular flange 60 through radially extending arms 63. The hub of this spider has mounted in it ball bearings 64 and 65 which are disposed at the upper and lower ends of the same. In the center of the bottom 11 of tray 10 40 is provided a boss 66 which has secured to it through a set screw 67 an upwardly extending post 68. Post 68 is turned to receive the inner races of the two bearings 64 and 65. By means of these two bearings the spider 61 is rotatably 45 mounted. A cap 69 secured to the upper end of the hub 62 covers the bearing 64 and prevents the entry of water into said bearings from above. The table 24 rests upon arms 71 extending outwardly from the flange 60 of spider 61 and is 50 centered with respect to the axis thereof through said flange. The flange is of such dimensions as to snugly receive the inner ring 33 of the table 24.

55 It will be noted that flange 60 extends above the surface of the table 24 and assists in preventing articles positioned on said table from traveling inwardly off the table. To further serve this purpose a guard 72 is employed which is constructed from sheet metal bent in cylindrical form with a curvature substantially equal to the curvature of the flange 60. This guard is bolted to a mounting 73 by means of bolts 74 and may be easily removed when access into the interior of the machine is desired. Mounting 73 is soldered or otherwise secured to the cover 18.

Inasmuch as the water motor C and the power transmission associated therewith form no particular feature of this invention, these parts have not been shown in detail. The water motor C is, however, constructed with a water wheel 75 which through a suitable train of gearing drives a friction pinion 76. This friction pinion engages a 70 75

friction gear 77 formed by the inner surface of the flange 60 of spider 61.

The spraying device D consists of a series of sprays 78 which are disposed above the rack B and another series of sprays 79 which are disposed below said rack. These sprays are interconnected by tubes 81 and are fed by a number of tubes 82 which are connected to a valve operated control mechanism 83 whereby hot and cold water are furnished to the sprays. This construction forming no feature of the invention has not been shown in the drawings, though it can readily be comprehended that a construction such as shown in the application for patent of Walter F. Ohme and Ray C. Stephan, Serial Number 741,078, filed August 23, 1934 may be used for the purpose.

The operation of the invention is as follows: As the water motor C operates rack B is rotated and the table 24 resting on the arms 71 thereof travel with it. Glasses, drinking vessels or other dishes are placed upon the rack through the opening 23 in housing A and the same rotate slowly through the machine. As the glasses or drinking vessels upon the table 24 pass the sprays 78 and 79 hot or cold water as desired is sprayed upon the interior and exterior thereof. The sprays of water from the sprays 79 pass between the rings 25 to 32 of table 24 and wash the drinking vessels upon the interior thereof. Due to the fact that the rings are constructed of flat wire a very small amount of resistance to the passage of water through the table results, whereby the full force of the water is directed against the drinking vessels and the same effectively cleaned. As the same time water is directed substantially to the entire interior area of the vessels, since the table offers a minimum amount of blocking to the passage of water. Due to the fact that the supporting members of the table are constructed of flat wire, point contact between the table and drinking vessels results so that only a minimum portion of the vessels are not subject to the cleansing action of the sprays. The result is that the glasses are almost perfectly washed when the same pass through the machine. I have found that a certain amount of vibration is set up in the machine which causes the glasses to slightly shift positions. Due to this fact the engaged portion of the vessels is varied so that all portions thereof may be thoroughly washed.

The advantages of my invention are manifest. Washing of drinking vessels is accomplished in a minimum length of time and with a minimum amount of water. A minimum amount of obstruction to the flow of water through the table is effected so that the desired results are readily attained. My improved table is considerably stronger than a cast table or a table constructed of round wire and has the added feature of minimum blocking of the travel of water through the same.

Changes in the specific form of my invention,

as herein disclosed, may be made within the scope of what is claimed without departing from the spirit of my invention.

Having described my invention, what I claim as new and desire to protect by Letters Patent is:

1. A perforate table comprising a plurality of supporting members in excess of three, constructed of flat strips bent in the form of circles of different diameters, said strips being arranged on edge in spaced concentric relation, the intermediate of said supporting members having aligning radially downwardly extending notches therein, and the outermost and innermost of said supporting members having openings extending therethrough and disposed in alignment with said notches, tie members constructed of flat strips provided with upwardly extending notches engaging the notches of said supporting members, and tongues on the ends of said tie members entering said openings.

2. A perforate table for use in a washing machine including a central supporting hub with a rim extending about the same, said table comprising a plurality of supporting members in excess of three, constructed of flat strips bent in the form of circles of different diameters, said strips being arranged on edge in spaced concentric relation, the intermediate of said supporting members having aligning radially downwardly extending notches therein, the innermost of said supporting members having openings extending therethrough and disposed in alignment with said notches, tie members constructed of flat strips provided with upwardly extending notches engaging the notches in said intermediate supporting members and tongues on the ends of said tie members entering said openings, said innermost supporting member resting on said rim and receiving stresses transmitted from the intermediate supporting members through said tie members.

3. A perforate table comprising a plurality of supporting members in excess of three constructed of flat strips bent in the form of circles of different diameters, said strips being arranged on edge in spaced concentric relation, the intermediate of said supporting members having aligning radially downwardly extending notches therein, and the outermost and innermost of said supporting members having openings extending therethrough and disposed in alignment with said notches, tie members provided with upwardly extending notches engaging the notches of said intermediate supporting members, and tongues on the ends of said tie members entering said openings, said intermediate supporting members being arranged with their edges in a common plane and said outer supporting member being of greater width than the intermediate supporting members and extending above the same to form a rim and to strengthen the outer portion of the table due to the weakening thereof caused by said openings.

WALTER F. OHME.
